UNITED STATES PATENT OFFICE

FRANK H. LONGYEAR, OF DETROIT, MICHIGAN, ASSIGNOR TO THERMAL ENGINEERING CORPORATION, OF DETROIT, MICHIGAN, A CORPORATION OF MICHIGAN

CHIP DRYING FURNACE

Application filed August 11, 1930. Serial No. 474,525.

This invention relates to furnaces and more particularly to a chip drying furnace and has as its objects to simplify, render more efficient and improve generally devices of 5 this character.

The invention has as one of its objects to provide a furnace designed to remove oil, water, moisture or cutting compound having oil as a base, from the surface of metallic 10 chips, borings, turnings, etc., of brass, aluminum, steel, iron and the like. The furnace may be used with equal facility for removing oil, water, etc., from small fabricated parts and the like.

15 In carrying out my invention the chips, fabricated parts or the like are conducted through a heated chamber and also subjected to direct flame impingement without injury to the metal due to oxidation.

20 My improved chip drying furnace consists of a furnace structure having primary and secondary combustion chambers, the former being provided with gas or fuel burners arranged for direct impingement of the flame 25 upon the material passing therethrough. Screw conveyors are provided for conveying the material to be treated horizontally through the furnace and the material is thereafter delivered to a vertical conveyor 30 and subsequently discharged. The furnace structure contemplates the provision of a secondary air manifold and pilot light for utilizing the vapors or gases given off due to 35 the volatilization of the oil to promote combustion in the secondary chamber thereby decreasing the amount of fuel used by the burners in the primary chamber.

40 Many advantages are realized from the use 45 of a chip drying furnace, particularly where magnetic separation of the chips is practiced. For instance, chips free from oil permit the separator to remove not only the larger pieces of metal but also the dust which in wet or moist chips, is held fast to the turnings by the moisture present. Dry chips permit a more even distribution of the chips through the separator and eliminate the possibility of picking up non-magnetic material 50 by the magnetic separator. As a result a

better product is obtainable for introduction into the melting furnace.

Where the chips are charged directly into the melting furnace the time heretofore required to permit the oil to burn off before the melting operation is started is eliminated and experience has shown that dry chips melt down considerably faster than those in which moisture is present when charged. Moreover, from the metallurgical standpoint the presence of oil, especially in metals as they are melted, is undesirable.

The several objects, advantages and novel details of construction of my invention will be made more apparent as this description 65 proceeds, especially when considered in connection with the accompanying drawings, wherein.

Figure 1 is a longitudinal sectional elevation view through a furnace constructed in accordance with my invention, and

Figure 2 is a vertical transverse sectional view taken substantially on the plane indicated by line 2—2 in Figure 1.

In general the furnace structure is fabricated from refractory brick and steel, the reference character 10 indicating the bottom thereof which is supported and reinforced by longitudinally extending I beams 11 and cross members 12, the longitudinal members being mounted on a foundation indicated generally by the reference character 13.

The top 14 of the furnace is of refractory brick suitably reinforced as are also the end walls 15 and 16. The reference character 17 indicates the side walls of the furnace.

Extending transversely of the furnace between the side walls 17 and arranged substantially intermediate the length of the furnace are a pair of downwardly converging baffles 18 which divide the heating chamber of the furnace into a primary combustion chamber 19 and a secondary combustion chamber 20. The bottom 10 of the furnace is provided with a pair of longitudinally extending channels 21 in which screw conveyors 22 are arranged. In the embodiment of the invention herein illustrated twin conveyors or a pair of conveyors are employed. Each screw conveyor is so constructed that

the portion 22' adjacent the hopper 23 has a smaller flight than the portion 22" of the remainder of the screw conveyor. However, these differential portions of each screw conveyor are carried on the same shaft and turn at the same speed. This conveyor construction permits a full feeding of the hopper and as the material passes from the smaller flight 22' to the larger flight 22" it will be thinned out and will be passed through the furnace in this condition thus permitting a better agitation during its travel through the furnace.

At the other end each of the conveyors deposits the material into a chute 24 which in turn deposits the material into an elevator 25 whereupon the material is carried upwardly and discharged through discharge aperture 26.

While any preferred or desired driving means may be provided for the conveyors, I have illustrated the shafts of the twin conveyors as provided with bevel gears 27 driven by a shaft 28. This shaft is driven by a chain 29 connected to a speed reducer 30, which in turn is connected by means of a chain 31 to a variable speed device 32 driven through chain 33 by means of a motor or the like 34. The elevator 25 is also preferably provided with a screw conveyor (not shown) driven by gearing 35 connected by chain 36 with the variable speed device 32.

One or more burners 37 are mounted in the wall 16 of the primary chamber 19 in such a manner that the flame thereof directly impinges upon the material being conveyed therethrough. These burners also heat the primary chamber and the hot gases pass down the adjacent refractory baffle 18 and through the conveyor troughs and into the secondary chamber 20.

While various types of burners may be employed I have found that particularly efficient results can be obtained with the use of a burner of the type shown in my copending joint application Serial No. 466,311. The burners 30 are preferably so constructed as to provide a slight excess of fuel to thus produce a reducing atmosphere providing a non-oxidizing condition within the furnace.

The top wall 14 over the primary combustion chamber 19 is provided with an opening 38 normally closed by a gravity safety door 39 hingedly mounted as at 40. The purpose of this door is to relieve the pressure of gases which might accumulate beyond a degree of safety in the primary chamber. This might occur from various causes but particularly so if the feed of the material though the furnace becomes so heavy as to prevent the escape of gas under the lower edges of the baffles 18 through the conveyor troughs.

The secondary chamber 20 is provided with a stack 40' provided with a break 41 intermediate its length to retard the draft so that

the efficiency of operation of the secondary chamber will not be adversely affected. An auxiliary stack 42 which is connected to the main stack and to the elevator adjacent the upper end thereof will conduct to the main stack any trapped gases that may be present in the elevator.

The reference character 43 indicates an air manifold by means of which air under pressure may be introduced into the secondary chamber. A pilot light 44 is also provided.

In the operation of the furnace the vapor or gas given off due to the volatilization of the oil on the chips or in the cutting compound where oils are present, are highly combustible when mixed with air. The purpose of the air supplied by the manifold 43 is to promote combustion in the secondary chamber and this combustion is controllable through the amount of air introduced through this manifold. Constant ignition of the locally produced combustible mixture is maintained by the pilot 44 and the heat obtained through this combustion in the secondary chamber readily preheats the material passing through the secondary chamber with the result that during continuous operation of the furnace it is possible to reduce the quantity of gas or fuel used in the burner 37 in the primary chamber.

It has been found that carbon is not formed in detrimental excess by reason of any over supply of fuels because the temperature of the furnace atmosphere at this point in the secondary chamber is fairly high and if any carbon should be formed the draft from the stack 40 carries light particles of carbon up the stack.

In operation the chips, fabricated parts or other material to be dried is deposited in the hopper 23 and conveyed longitudinally through the furnace by the twin conveyors 22. The material upon entering secondary combustion chamber 20 is preheated and in subsequently passing through the secondary chamber gives off a vapor as its temperature is raised. In passing through the furnace this action increases until all of the volatile compound is removed. In the primary chamber 19 the temperature is higher than the vaporization point of any of the oil or cutting compounds so that prior to being discharged all oil, water, moisture or cutting compounds having oil as a base are removed. As previously mentioned the burners 37 produce a completely reducing atmosphere so that the materials being treated are uninjured through oxidation.

The material at the discharge end of the furnace is deposited through chute 24 to the elevator 25 where it is discharged through the discharge opening 26.

Various modifications may suggest themselves to those skilled in this art and to this end reservation is made to make such changes

as may come within the purview of the accompanying claims.

What I claim as my invention is:

1. In a drying furnace of the character described having a heating chamber, means for dividing the heating chamber into a primary chamber and a secondary chamber, means for conveying the material to be dried through said chamber, a burner for heating said primary chamber to drive combustible gases from said material, and means for promoting combustion of said gases in said secondary chamber.
2. In a drying furnace of the character described having a heating chamber, means for dividing the heating chamber into a primary chamber and a secondary chamber, means for conveying the material to be dried through said chamber, a burner for heating said primary chamber, and means including a manifold for introducing air under pressure into said secondary chamber to promote combustion of combustible gases therein, as and for the purpose set forth.
3. In a furnace comprising a heating chamber for drying chips and the like, means for conveying the material to be dried through the furnace, baffle means intermediate the heating chamber of the furnace dividing the same into a primary chamber and a secondary chamber, burners for heating said primary chamber, the gas resulting from the volatilization of oil on said chips being present in said secondary chamber, and means for promoting the combustion of said gases including a manifold for introducing air under pressure and a pilot light for maintaining said combustion, for the purpose set forth.
4. In a structure of the class described, a furnace comprising a heating chamber, means in said furnace dividing the heating chamber thereof into a primary chamber and a secondary chamber, a material conveyor extending through said chambers, a burner for heating one of said chambers, and means utilizing the gases of volatilization for promoting combustion in the other of said chambers.
5. In a device of the class described, a furnace having a heating chamber, baffle means intermediate said heating chamber for dividing the same into a primary chamber and a secondary chamber, burner means for heating one of said chambers and a gravity actuated safety device in the wall of said latter chamber, for the purpose set forth.
6. In a chip drying furnace of the character described, a furnace structure including a heating chamber, a screw conveyor extending longitudinally therethrough, said conveyor having a portion extending beyond the furnace at one end thereof, this projecting portion of the conveyor having a smaller flight than the remainder of the

conveyor and a hopper arranged above the said projecting portion of said conveyor, for the purpose set forth.

In testimony whereof I affix my signature.

FRANK H. LONGYEAR.
